UNITED STATES PATENT OFFICE.

MATHIAS ARMBRUSTER, OF COLUMBUS, OHIO.

PHOTOGRAPHER'S SCENERY.

SPECIFICATION forming part of Letters Patent No. 373,794, dated November 22, 1887.

Application filed July 18, 1887. Serial No. 244,617. (No model.)

To all whom it may concern:

Be it known that I, MATHIAS ARMBRUSTER, a citizen of the United States, residing at Columbus, in the county of Franklin and State of Ohio, have invented certain new and useful Improvements in Photographers' Scenery; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to improvements in photographers' backgrounds; and it consists of the peculiar combination of devices and novel construction and arrangement of parts, as will be hereinafter fully described, and particularly pointed out in the claims.

Heretofore it has been the common practice for photographers to employ a number of independent separate backgrounds to comp'y with the various requirements of exterior and interior views, light and dark scenes, &c.; but the employment of a number of these backgrounds is objectionable, owing to the size thereof and the limited amount of space or room in ordinary photographic galleries, which renders the use and adjustment of the backgrounds exceedingly difficult. It is also very desirable to have backgrounds of larger area than a single background of ordinary size for the purpose of taking groups; but ordinary backgrounds cannot be adjusted together to present a good surface, and it is impossible to cause the meeting edges thereof to match so that the joint between the backgrounds is invisible.

It is the object of my invention to overcome these difficulties and inconveniences hereinbefore set forth by providing a single background having a number of differently-painted scenes, which can be adjusted with ease and quickness to provide a larger or smaller area, and of widely different characters to suit the circumstances, either interior, exterior, and light and dark views being obtained at the will of the photographer. By combining a comparatively large number of scenes of varying characters and shades and arranging them into a convenient single background, so that they

can be easily adjusted to present different combinations, I am enabled to produce a device which fulfills a long-felt want with photographers, as the background of my invention 55 can be made at a reduced cost, below the price of a set or number of the ordinary backgrounds, it requires a very much smaller space for storage and adjustment, can be changed very quickly and easily within a shorter time, 60 and can be adjusted for the use of one, two, or more persons, or a group.

A further object of my invention is to provide the background with means for adjusting the sections to bring the contiguous adjoining 65 edges thereof into close proximity and render the joint between the same invisible.

In the accompanying drawings, which illustrate a photographer's background embodying my invention, Figure 1 is a perspective 70 view showing the sections adjusted in line with each other. Fig. 2 is a like view showing the outer end sections adjusted so that the contiguous edges of the scenes match and form a background of one-third less area than 75 that presented in Fig. 1. Fig. 3 is a vertical cross sectional view on the line $x-x$ of Fig. 2. Fig. 4 is a view corresponding to Fig. 2, showing the end sections or wings of the background adjusted to bring the outer vertical 80 edges of the scenes into proximity and provide a scene of a different character from that shown in Fig. 2, although formed by the same sections of the background. Fig. 5 is a vertical sectional view on the line $x-x$ of Fig. 1, to 85 show the peculiar mechanism employed for adjusting one of the end sections toward the section adjoining the inner edge thereof to conceal the joint between the two sections.

Referring to the drawings, in which like 90 letters of reference denote corresponding parts in all the figures—

A B designate the end sections or wings of a photographer's background embodying my invention, and C the intermediate or middle 95 section, which is adjustable in line with the end section to form a larger area or surface, or can be thrown in rear of the end sections and concealed from view thereby to adapt the end sections to abut together and form a background of smaller area.

Although I have shown and described a

background composed of three sections, still I do not desire to be confined to the use of any specific number of the same. Each section of the background is formed by a skeleton frame, 5 D, over which is stretched a canvas or other covering, D', which is painted in the desired manner to represent interior and exterior views and light and dark shades. Both sides of each frame are covered by the painted canvas or other covering D', and all the scenes differ from one another, either in the character or shade, so that the various combinations formed by the scenes are different. The end sections or wings, A B, of the background are 10 disposed in rigid adjustable frames E F, respectively, these frames being substantially similar in construction. Each rigid frame E or F comprises a vertical bar, e, and two horizontal bars, f f', which are arranged at the extremities of the vertical bar and parallel with each other, the bars e f f' of each frame being joined and formed in any suitable manner so that they will occupy the same relative positions at all times, the inner ends of the horizontal arms f f' of the frames being perforated, 15 as at e', for a purpose presently described. Each of the end sections has horizontal central slots, g, formed in the upper and lower horizontal bars of the skeleton frames thereof, 20 and through these slots of each frame is passed a vertical shaft, G, which has its ends secured or fixed in one of the frames E or F by means of nuts and washers g', said shaft serving as a center around which the end sections, A B, are 25 free to swing or turn within the supporting-frames E F. The end sections are capable of turning freely in the supporting-frames without hindrance therefrom or from one another, and they are also capable of a limited side or lateral movement in the supporting-frames, for a 30 purpose presently described, this lateral movement being permitted by reason of the stationary shafts G passing through the horizontal slots in the skeleton frames of the end sections.

The intermediate section, C, of the background is permanently attached to the supporting-frames of the end sections or members in such a manner that the intermediate section 35 can be adjusted in line with the end sections to provide a larger background for groups and large objects, as seen in Fig. 1, or it can be adjusted in rear of the end sections and entirely out of the way of the latter, as 40 seen in Figs. 2 and 3. The intermediate section is connected to the supporting-frames E F by means of four pairs of arms or links, H H', two pairs of which are arranged at the upper end of the sections and two pairs at the lower ends 45 thereof. The inner extremities of each pair of links or arms are pivotally connected to the corners or angles of the intermediate section, C, by a suitable pivotal device, as at h, while the outer ends of the pairs of arms or links H 50 H' are fitted on extended ends of the vertical stationary shafts G. The links or arms are thus pivotally connected to the center of the

supporting-frames E F, and they serve to support the intermediate section, C, in a vertical position at all times without reference to the 70 position that the intermediate section occupies to the remaining end sections or members of the device. The arms or links of each pair are separated and held parallel with each other by interposed washers, h², so as to provide a space between the same which is of uniform width, and to permit the inner free end of one of the horizontal arms of the supporting-frame E or F to fit snugly therein 75 when the arms or links lie parallel with and inclose said arms of the frame, as they do when the intermediate section, C, is adjusted in line with the end members, A B. Each of the parallel arms or links is further provided with aligned openings h³ at such a point therein as 80 to register or coincide with the apertures e' of the supporting-frames when the arms lie parallel with the horizontal arms f f' of the frames, and removable pins H² are passed through the aligned openings e' h³ to hold the links or arms 85 H H' parallel with the frames E F, and thus maintain the members A B C in their proper adjusted positions.

At the upper and lower corners of the rigid supporting-frames E F are formed horizontal 90 interiorly-threaded openings i, in which are fitted binding-screws I I', which are adapted to impinge against the outer vertical edges of the end sections or members, A B, to force them laterally in the rigid supporting-frames 95 against the tension of retracting-springs J, which in the present instance are made in the form of rubber blocks or cushions that are inserted in the horizontal slots g of the frames D of the end members or sections, between the vertical shafts G and the ends of the slots. These retracting-springs serve to hold the 100 swinging rotary end members or sections, A B, in the rigid supporting-frames E F, so that the end members can turn freely around the vertical shafts, and the springs are compressed to 105 serve as cushions when the binding-screws are tightened in the rigid supporting-frames to force or press the end sections toward the intermediate section or each other. By permitting the end sections to have a limited lateral play in the rigid supporting-frames and providing the retracting-springs, the end sections can be readily forced inwardly to close the 110 joint between the same and an adjoining section by the binding-screws, and when the latter are released, the end members are forced outwardly to enable them to be easily reversed or turned in the supporting-frames without 115 striking the intermediate member or section, C. The end sections can thus be adjusted laterally within the supporting-frames to close the joint and render it practically invisible in the 120 proof, also reversed with ease and facility to bring their reverse painted surfaces to view, and held rigid in the supporting-frames, and thereby adjustable therewith.

Each scene on the painted surface of the sections or members A B C is complete in itself

to serve as a background for taking individual photographs, and the series of scenes on one side of the background are painted so that either of the vertical edges will match when 5 the scenes are adjusted for use. By painting the sections or members in this manner I am enabled to provide a large number of different views which are formed by single numbers or sections or combinations thereof, and 10 the members can be easily and quickly adjusted for use.

In the embodiment of my invention shown in the accompanying drawings, having three members or sections, they are painted to represent exterior views, and I can form out of 15 these three views eight different backgrounds, which I will now explain. Three backgrounds are formed by the three separate members, which can be used independently of each other, 20 as is obvious, and it may be desirable to adjust one of the other sections at one side of the section in use, to answer as a reflector or break the force of the rays of light, as will be readily understood by those skilled in the art. 25 A fourth scene is formed by the use of the members A C, and a fifth by the members B C, which are adjusted in line with each other, and the end member in each case is forced laterally toward the intermediate member to close 30 the joint between the two members, as will be readily understood. A sixth scene is presented by arranging all three of the members in line with each other, and the members are held in their proper positions by means of the pins 35 and the tightening-screws, which latter close the joints between the sections. A seventh scene is formed, as seen in Fig. 2, by adjusting the end members, A B, so that the inner approximate edges thereof abut together. This 40 adjustment is effected by first removing the pins H² to disconnect the arms or links H H' from the supporting-frames, then forcing the intermediate section rearwardly, so that it is supported by the arms or links which lie at 45 right angles to the supporting-frames, and then adjusting the latter frames toward each other until the inner free ends of the arms f f' thereof meet. The apertures e e' in the arms e of the supporting-frames align, the pins H² are passed 50 through the same to connect the frames together, and the binding-screws tightened to force the end members close together. The eighth scene (shown in Fig. 3) is formed by reversing the end members or sections, A B, in 55 their supporting-frames E F to bring their outer edges into close juxtaposition, and thereby cause the same to abut together to present a scene the reverse of that formed by the two members in the seventh adjustment, just de- 60 scribed and shown in Fig. 2. After the end members or sections have been reversed in their supporting-frames the parts are adjusted in the manner hereinbefore described—i. e., the intermediate section is passed between the 65 end sections and forced in rear of the same, which latter sections are spread apart to permit the passage of the intermediate section,

and the supporting-frames E F adjusted inwardly toward one another to cause the approximate edges of the end members to abut 70 together, after which the pins H² are inserted in the aligned openings e' of the frames, to hold the same together, and the binding-screws tightened.

In describing the adjustments of the members of my improved background I have assumed that only one of the sides of each member is painted; but I propose to cover both sides of the members or sections with different scenes, and thus increase the number of 80 combinations to twice the number herein specified, or sixteen in all. Of course the members or sections can be painted to represent different scenes and subjects, according to the wishes of the photographer, and light and dark shades 85 can also be given to the scenes, &c.

The operation of my invention will be readily understood from the foregoing description, taken in connection with the accompanying drawings. The background is supported in its 90 upright position by means of suitable feet or bases, K, which are rigidly secured to the lower outer corners of the supporting-frames E F, and for the purpose of readily moving the device from one place to another rollers 95 or casters can be secured to the feet. The central or intermediate section may also be provided with a strong metallic foot to give the frame a firm upright position. If desired, the pins H² may be secured at one end 100 to flat leaf-springs, which have one end permanently secured to the supporting-frames, the pins being thus prevented from becoming detached from the frames and lost. The members or sections can be adjusted at various 105 angles to each other, instead of in line, as may be desired, and when thus adjusted the locking-pins H² are dispensed with.

While I deem the mechanism and devices herein shown and described as best adapted 110 for carrying my invention into practice, still I do not desire to be limited to the exact details of construction and form and proportion of parts, as I am aware that numerous changes can be made without departing from the spirit 115 or sacrificing the advantages of my invention.

Having thus fully described my invention, what I claim as new, and desire to secure by Letters Patent, is—

1. A photographer's background consisting of the adjustable frames, and members or sections mounted in the said frames so that the vertical edges of the members abut together, substantially as and for the purpose described.

2. A photographer's background consisting of adjustable frames connected together and members or sections mounted in and adjustable with the frames, said members abutting together at their contiguous vertical 130 edges and pointed, so that the designs or scenes thereon match at the vertical edges of the members, substantially as and for the purpose described.

3. A photographer's background consisting of end members or sections, adjustable frames in which the end members are mounted, and an intermediate member adjustable in line with and between the end members, said intermediate member being also adjustable in rear of the end members and frames to adapt the two end members to abut together at their vertical edges, substantially as and for the purpose described.

4. A photographer's background comprising end members and an intermediate member connected by intermediate devices with the end members and adjustable in line with and between the same, substantially as and for the purpose specified.

5. In a photographer's background, the combination of the supporting frames adjustably and detachably connected together, end members mounted in and adjustable with the frames, an intermediate member, and links connecting the intermediate member to the supporting-frames, whereby the supporting-frames and end members can be adjusted laterally of each other to have an intermediate space between the same, into which space the intermediate member or section is adjusted to lie in line with the end members, substantially as described.

6. A photographer's background consisting of suitable carrying-frames having the open contiguous sides, and members or sections mounted in said frames and capable of lateral or edgewise movement therein to close the joint between the meeting edges of the sections, substantially as described.

7. A photographer's background consisting of carrying-frames, members or sections mounted in the frames, and devices connecting the members to the frames in such a manner as to permit the members to have a horizontal swinging movement around a vertical center and a lateral edgewise movement toward one another, substantially as and for the purpose described.

8. In a sectional background, the combina-

tion of suitable carrying-frames adjustable relatively to each other, members adjustably mounted in the frames, and devices for moving the members laterally in the frames to close the joint between the members, substantially as described.

9. In a sectional background, the combination of suitable carrying-frames, members mounted in the frames and capable of lateral movement therein, spring devices for normally holding the frames in position to turn freely in the frames, and means for adjusting the sections or members against the tension of the spring devices, substantially as described.

10. In a sectional background, the combination of suitable carrying-frames, members or sections having longitudinal slots mounted in the frames, springs for normally holding the members in the supporting-frames so as to turn freely therein, and binding-screws working in the supporting-frames and impinging against the members to move the same laterally in the supporting-frames, substantially as described.

11. In a sectional background, the combination of suitable carrying-frames, members mounted in the frames, an intermediate section or member, and links connecting the intermediate member with the supporting-frames, substantially as and for the purpose set forth.

12. In a sectional background, the combination of suitable carrying-frames, members or sections mounted in the frames, an intermediate section, links connecting the intermediate section to the carrying-frames, and devices for holding the links in fixed position with relation to the carrying-frames, substantially as described, for the purpose set forth.

In testimony whereof I affix my signature in presence of two witnesses.

MATHIAS ARMBRUSTER.
